UNITED STATES PATENT OFFICE.

JOB W. PETTENGILL, OF ROCKFORD, ILLINOIS.

DESIGN FOR CROQUET IMPLEMENTS.

Specification forming part of Design No. 5,556, dated February 20, 1872.

To all whom it may concern:

Be it known that I, JOB W. PETTENGILL, of Rockford, county of Winnebago, State of Illinois, have invented a new and Improved Design for Croquet, of which the following is a full, clear, and exact description, reference being had to the accompanying drawing.

Various methods have been adopted for marking the balls, mallets, and turning stakes of croquet sets, in order that each person may readily determine, first, which is his own ball, and, second, the order in which the players are to follow each other. For the purpose of cheapening the process of marking the parts, while at the same time furnishing a design which shall enable a player to see at a glance which ball corresponds to his mallet, I have invented the following design for croquet, which consists essentially in a particular system of spacing and grouping circumferential lines upon the different pieces, as I will now explain.

Ball number one I mark by a single central line; numbers two and three, by lines about

equidistant from each other; number four, by two lines in the center and one line upon each side, with a shorter space between the two central lines than between the group and the outside lines, the two ribs on the central portion of the mallet favoring this arrangement, as will be readily seen from the drawing. Number five I designate by one line in the center, with a group of two upon each side; number six, by three groups of two lines each; number seven, by a group of three in the center, with a group of two upon each side; then one blank ball and one blank mallet completes the set of eight.

I am aware that croquet has been marked with simple lines under a special arrangement before; but

What I claim as my invention is—
The herein design for croquet, consisting of lines grouped and spaced as described.

JOB W. PETTENGILL.
